MOBILE VAPORIZER SYSTEM

Alvin W. Peck, Bartlesville, Okla., assignor to
 Phillips Petroleum Company, a corporation of
 Delaware

Application December 29, 1945, Serial No. 638,405

6 Claims. (Cl. 126—271.2)

1

This invention relates to vaporizers. In one of its more specific aspects it relates to vaporizers for use with liquefied petroleum gases. In a still more specific aspect it relates to vaporizers which are adaptable for use in conjunction with tractor-weed burner assemblies.

Flame methods for the killing of weeds have gained in usage in the cultivation of certain crops as a substitute for mechanical cultivating or cutting methods and especially for hand methods. It is for the purpose of further widening the use of flame methods of weed killing and/or cultivation that my invention is mainly directed.

One object of my invention is to provide a liquid hydrocarbon fuel vaporizer for use with weed burning equipment on tractors.

Another object of my invention is to provide a liquid hydrocarbon fuel vaporizer for use with weed burning equipment on tractors wherein the vaporizer serves to vaporize fuel for the tractor as well as for the burner.

Still another object of my invention is to provide a liquid hydrocarbon fuel vaporizer wherein an exhaust muffler mechanism serves to furnish heat for the vaporization of the fuel.

Still another object of my invention is to provide a liquefied petroleum gas vaporizer for use on a tractor-weed burning assembly wherein the tractor muffler serves to furnish heat to vaporize liquefied petroleum gas for fuel for the weed burner as well as for the propulsion of the tractor.

Still other objects and advantages of my invention will be obvious to those skilled in the art from a careful study of the following description, which taken in conjunction with the attached drawing forms a part of this specification.

In the drawing, Figure 1 represents diagrammatically the assembled apparatus.

Figure 2 is a diagrammatic cross sectional view of a preferred form of my muffler-vaporizer apparatus.

Referring now to the drawing and especially to Figure 1, a tractor assembly 11 is illustrated embodying the muffler-vaporizer shown in detail in Figure 2. The tractor itself may be substantially any kind or type of tractor. It is adapted, however, for the use of a relatively low-boiling type of hydrocarbon fuel. As, for example, equipment is readily available, and in fact in common use, for the storage, transportation and use of liquefied petroleum gases, such as propane, butane or mixtures of these.

Such hydrocarbons as propane or butane boil at temperatures below normal atmospheric temperature and therefore must be stored in pressure

vessels. For the carburetion of such a fuel, and especially for the vaporization of the fuel at a relatively rapid rate, the vaporization equipment becomes so chilled due to the latent heat of evaporation that its usefulness becomes questionable. I have found that by the use of a modified type muffler in combination with a conventional type muffler, that relatively rapid evaporation may be continued for long periods of time thereby providing successful and practical operation.

Referring again to the tractor assembly 11 of Figure 1, an exhaust manifold pipe 12 is connected with a pipe 13 which is equipped with a cutout valve 14, adapted to move around a pivot point 15. This cutout valve is opened and closed through movement of a rod 17 which is attached to cutout valve 14 through a lever arm 18 and pivot member 16. In this assembly the cutout valve member 14, is of course, located inside of the pipe 13. The pivot member 15 extends through the walls of the pipe 13 and may be attached rigidly to the valve member 14. The arm 18 is attached to one end of said pivot member 15 and is situated outside of the pipe 13. At the opposite end of the arm 18 is of course the pivot member 16 and at this point is attached the cutout valve actuating rod 17.

This actuating rod 17 is moved by the action of a bellows 19, the operation of which will be hereinafter explained.

As mentioned hereinbefore one end of the pipe 13, which carries the cutout valve 14, is attached to the exhaust manifold pipe 12. The other end of the pipe 13 is adapted to be attached to two pipes, identified by numerals 20 and 21. The pipe 21 is adapted to convey exhaust gases from the manifold 12 by way of cutout pipe 13 to a conventional muffler 23 while pipe 20 carries exhaust gases through my vaporizer-muffler 22. From this vaporizer-muffler a pipe 31 serves as an exhaust pipe.

Connected to the vaporizer-muffler 22 is a pipe 26, carrying a valve 32, which pipe is adapted for conducting petroleum gas fuel to a burner mechanism 33. An arm 34 serves mainly as a support to steady the burner during operation and at times when the tractor is in motion.

A pipe 27 is adapted to carry vaporized fuel from the vaporizer to a carburetor 35 for tractor power use and has a throttle valve 43 positioned therein between said vaporizer and said carburetor. A pipe 25 extends from the lower extremity of a pressure fuel tank 24 to the vaporizer 22 and has a cut-off valve 45 posi-

tioned therein. Filler valve 46 is positioned in the inlet to pressure fuel tank 24.

The vaporizer-muffler mechanism 22 is shown in cross sectional detail in Figure 2. An interior portion 37 is for the most part a conventional muffler. This muffler portion is bounded by a sidewall 38 and end walls 39. Several baffles 36, situated within the muffler walls are intended merely to be diagrammatic since any desired type of baffles may be used within such a muffler.

Outside the cylindrical muffler wall 38 is a concentrically spaced outer cylindrical wall 40. This outer wall 40 and the muffler wall 38 are so arranged as to form an annular space 30 therebetween. This annular space 30 is the actual vaporizing space for the vaporization of the liquefied petroleum gas, and heat for this vaporization is supplied through the muffler wall 38.

The tube or pipe 25 which carries liquid fuel from its storage tank 24 to the vaporizing space 30 contains a flow control valve 42 which in turn is connected by way of a tube 41 to the vaporizing chamber 30. This flow control valve 42 is so adjusted that as pressure in the vaporizing space 30 reaches a predetermined maximum value, the valve operates to throttle or to close off liquid fuel flow through pipe 25. Similarly, when the pressure of the vaporized gas reaches a predetermined minimum value, the valve 42 operates to open and permit flow or to permit increase of flow of liquid fuel to be vaporized. Such a flow control valve is known in the art and is readily obtainable from commercial supply houses.

A chamber 28 contains such a material as ethylene glycol, and this material has fluid communication with the bellows control apparatus 19 through a tube 29. This fluid controller mechanism is intended as an operating control to prevent overheating of the vaporizer mechanism. When the fluid in chamber 28 becomes heated, an increase of fluid pressure is transmitted by way of tube 29 to the interior of a main bellows 43. When this pressure increase occurs the main bellows becomes extended and the rod 17 moves in a downward direction. To magnify this movement of rod 17, an interior bellows 44 is installed in the mechanism as shown in Figure 2, and upon increase of fluid pressure in the space between the two bellows, the top of the interior bellows also moves downward. This combined movement moves rod 17 and accordingly pivot point 16 to such an extent that the cutout valve 14 rises to close off or to throttle the flow of hot exhaust gas from the manifold 12 to the vaporizer 22. Then when the vaporizer 22 cools to such an extent as to cause a decrease in pressure in the bellows assembly 19 to a predetermined value, the rod 17 and pivot 16 rise to open the cutout valve 14 and thereby increase flow of hot exhaust gas through the vaporizer. Commercially available bellows controllers are adjustable to the extent that temperatures for opening valve 14 and for closing valve 14 may be determined by considerations for best overall operation. Other fluid than ethylene glycol may be used in such a controller, as desired, and depending at least in part upon the type of controller selected and upon the temperature of operation.

In the operation of this vaporizer mechanism for the dual purpose as herein shown, liquefied petroleum gas to be vaporized passes from pressure storage tank 24 through pipe 25 and through the flow controller 42 into the vaporizing space

30 of the vaporizer 22. Heat from the engine's exhaust gases passes through the wall 38 and in so doing causes evaporation of the liquid fuel in the chamber 30. If the flow of liquid entering chamber 30 through tube 25 is more rapid than the equivalent removal of fuel vapor through pipes 26 and 27, pressure will build up in the chamber 30 and be transmitted through tube 41 to cause the control valve 42 to close. And when pressure in the vaporizer 30 decreases to a predetermined value this valve 42 then opens to permit flow of liquid. Throttle valve 43' operates to prevent gas under excessive pressure from reaching carburetor 35. Valve 43' causes a pressure drop in line 21 when pressures therein are higher than those desired for operation of carburetor 35. Filler valve 46 operates to prevent the escape of gas through the fuel pressure tank inlet. If desired, pressure of fluid flowing into vaporizer-muffler 22 can be greatly reduced by partially closing cut-off valve 45.

During such times as when the weed burner 33 is not in operation the evaporation load on the evaporator 22 is relatively small, and the evaporator tends to overheat. This tendency is reduced or controlled by the fluid-bellows control mechanism in such a manner that as the fluid in chamber 28 becomes hot, an increase of fluid pressure is transmitted through tube 29 into the bellows assembly. This assembly operates to lower the rod 17 and accordingly to raise the cutout valve 14 and to cause the exhaust gases from the engine to flow through the auxiliary muffler 23 in place of through the evaporator 22. In this manner the evaporator 22 does not become overheated. Then as evaporator 22 cools, the fluid in chamber 28 cools and contracts reducing fluid pressure which allows rise of the rod 17. When rod 17 rises, the cutout valve 14 lowers thereby causing all or a part of the hot exhaust gases to pass through the vaporizer 22.

In this manner sufficient exchange heat is readily available to vaporize sufficient liquefied petroleum gas to operate the tractor engine and the weed burner. Overheating of the vaporizer is guarded against and flow of liquid fuel into the vaporizer is controlled.

The vaporizer-muffler unit 22 should be well constructed and especially so from the point of view of gas leakage. Exhaust gas should not leak into the vaporizing chamber and likewise vaporized petroleum gas should not leak into the muffler portion of the vaporizer.

Materials of construction may be selected from among those commercially available. They should be able to withstand gas engine muffler temperatures, etc. The type and kind of control bellows may be selected from among those available. Other means for operating the cutout valve 14 may be employed, if desired, but such means should preferably be responsive to temperature of the vaporizer 30.

It will be obvious to those skilled in such art that many variations and modifications of my invention may be made and yet remain within the intended spirit and scope of my invention.

Having disclosed my invention, I claim:

1. In a system having a liquefied petroleum gas storage tank, a separate liquefied petroleum gas vaporizer assembly having an internal combustion engine type muffler with an engine exhaust gas inlet and an exhaust gas outlet; a jacket surrounding said muffler and forming an enclosed space therebetween, a liquefied petroleum gas conduit communicating between said

storage tank and said enclosed space, a flow control valve situated in said liquefied petroleum gas conduit and actuated by pressure within said enclosed space, a gas outlet tube from said enclosed space, said engine exhaust gas inlet comprising a tube adapted for communication with an engine exhaust manifold pipe and having a side opening, and means for opening said side opening and closing said exhaust gas inlet and opening said exhaust gas inlet and closing said side opening to alternatively divert the gases from said muffler.

2. The liquefied petroleum gas vaporizer assembly of claim 1 wherein the gas outlet tube has a throttle valve therein.

3. The liquefied petroleum gas vaporizer assembly of claim 1 wherein said means for opening and closing said side opening is adapted to be responsive to the temperature of said jacket.

4. In a mobile vaporizer system including a gas consuming internal combustion engine power plant; a fuel supply system comprising in combination a muffler having an inlet and an outlet, a jacket surrounding at least a portion of said muffler and forming an enclosed vaporizer space therebetween, an exhaust gas conduit connecting said internal combustion engine and the inlet of said muffler, a liquefied petroleum gas storage tank, a first conduit connecting said storage tank and said jacket, a second conduit connecting said jacket and said internal combustion engine, a third conduit extending from said jacket, said third conduit being for connection with any additional gas consuming device which is movable therewith, a flow control valve in said first con-

duit, said flow control valve being responsive to pressure within said vaporizer space, a flow control valve in said third conduit; an exhaust gas outlet intermediate the ends of said exhaust gas conduit, a cutout valve in said exhaust gas outlet to divert gases from said muffler, and actuating means for opening and closing said exhaust gas outlet connected to said cutout valve.

5. The mobile vaporizer system of claim 4, wherein said actuating means is temperature responsive and extends between said jacket and said cutout valve.

6. The mobile vaporizer system of claim 4, wherein a throttle valve is positioned in said second conduit.
